OTHER PUBLICATIONS

U.S. Design Patent Application for Optical Scanner filed the same date of this application of Modest Khovaylo, Scott Henderson, Steven Vordenberg, Kevin Lozeau and Davin Stowell.

U.S. Design application Ser. No. 29/121,951, filed Apr. 17, 2000 for Scanner of Modest Khovaylo, David Farrage, Max Burton, Steven Vordenberg, Kevin Lozeau, and Davin Stockwell.

(List continued on next page.)

Primary Examiner—Freda Nunn

(57) **CLAIM**

The ornamental design for an optical scanner, as shown and described.

DESCRIPTION

FIG. 1 is an isometric view of an optical scanner showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is an enlarged, partially cut away, left side elevational view thereof with a front, left portion removed to more clearly show the front contour;

FIG. 9 is an isometric view of a second embodiment of an optical scanner showing our new design;

FIG. 10 is a top plan view of the second embodiment;

FIG. 11 is a bottom plan view of the second embodiment;

FIG. 12 is a front elevational view of the second embodiment;

FIG. 13 is a rear elevational view of the second embodiment;

FIG. 14 is a left side elevational view of the second embodiment;

FIG. 15 is a right side elevational view of the second embodiment; and,

FIG. 16 is an enlarged, partially cut away, left side elevational view of the second embodiment with a front, left portion removed to more clearly show the front contour.
